(57) **CLAIM**

The ornamental design for a monitoring system, as shown and described.

DESCRIPTION

FIG. 1 is a top perspective view of a monitoring system, showing our new design;

FIG. 2 is a front side view thereof;

FIG. 3 is a rear side view thereof;

FIG. 4 is a right side view thereof;

FIG. 5 is a left side view thereof;

FIG. 6 is a top plan view thereof; and,

FIG. 7 is a bottom plan view thereof.

The broken lines in the drawing views are for illustrating portions of the monitoring system that form no part of the claimed design; the broken lines form no part of the claimed design.
